UNITED STATES PATENT OFFICE.

DANIEL R. MURPHY, OF NEWARK, ASSIGNOR OF ONE-HALF TO GURDON B. JOHNSON, OF GRANVILLE, OHIO.

LOCOMOTIVE.

SPECIFICATION forming part of Letters Patent No. 279,102, dated June 5, 1883.

Application filed January 2, 1883. (No model.)

To all whom it may concern:

Be it known that I, DANIEL R. MURPHY, a citizen of the United States, residing at Newark, in the county of Licking and State of Ohio, have invented certain new and useful Improvements in Locomotive-Engines, of which the following is a specification.

My invention relates to improvements in locomotive-engines in which the steam-cylinders are placed between the driving-wheels, and has for its object the proper relative distribution of the weight upon the pilot and driving wheels. In the construction shown, the major portion of the weight is sustained by the driving-wheels, one pair thereof being placed in the rear of the fire-box, and the other pair in front of the longitudinal center of the boiler, whereby the weight of the engine-furnace, and its appurtenances is sustained by the driving-wheels, while sufficient weight is retained upon the pilot-truck to insure the safety of the engine while rounding curves upon the track. I accomplish these objects by the construction shown in the accompanying drawing, in which is represented a side elevation of a locomotive constructed according to my invention, the cylinder being in section to show the continuous piston-rod and its connections.

In the drawing, one of the cylinders A is clearly shown attached to the frame A', and located centrally between the driving-wheels B, with a continuous piston-rod, C, projecting from both sides of the piston C, and passing through both heads D of the cylinder to the cross-heads, whereby it is united to one end of the main connecting-rods F, and the opposite ends of said connecting-rods embrace the crank-pins of the driving-wheels. The cross-heads are provided with suitable guides, E', that are connected at one end to the cylinder-heads, and at the rear end to a yoke, E'', in the manner usually found in locomotive-engines.

A steam-pipe, G, leads from (each side of) the dome H to the steam-chest I. This steam-pipe is provided with a globe-valve, J, to shut the steam wholly off from one or both of the cylinders when desired, and thus remove the danger resulting from the accidental opening of the throttle-valve.

K shows the exhaust-pipe leading from the steam-chest I to smoke-box L.

The cylinders A are bolted to the side of the locomotive-frame, and within each steam-chest I is placed the slide-valve, having at one end the valve-rod I², the extremity of which is united to the main rocker-arm I³. The opposite end of said valve carries a rod that is united to or forms an extension of the piston-rod of the small cylinder a, suitably secured to the end of the steam-chest I. The small cylinder a has a steam-chest, within which is placed a slide-valve that is operated by means of the rod e, pivoted to one end of the double rocker-arm f. The latter is pivoted to the frame, and its lower end is provided with a connecting-rod, g, that is pivoted to and operated by the main rocker-arm I³. Steam is brought to the steam-chest of the small cylinder a through the pipe h, issuing from the main steam-pipe G, and it exhausts into the exhaust-pipe K of the main cylinder. The shaft of the rocker-arm I³ is provided with an arm pendant therefrom, and its lower end has a pin that enters the segmental link I⁵, and the latter is connected in the usual manner with the eccentrics on the front driving-wheels' axle.

By the arrangement of driving-wheels, cylinders, and pilot-truck, above described, it will be seen that nearly the whole weight of the engine is supported by the driving-wheels, while the front truck, T, having preferably only two wheels, has sufficient adhesion upon the rails to insure safety in leading the engine, and as the usual parallel rods uniting the driving-wheels are dispensed with, the accidents caused by their breakage cannot happen in this case. The fire-box M is made also longer than usual, to provide any desired amount of steam. The piston of the main cylinder being supported by the cross-heads at the end of each piston-rod, the internal surface of the cylinder is in a great measure relieved of the weight of the piston and retains its cylindrical form while in use.

I am aware that locomotives have been provided with a pair of driving-wheels in front of the fire-box, a pair in the rear thereof, and cylinders adjoining the pilot-truck, and that other locomotives have been provided with

cylinders between the driving-wheels; but they all differ from mine in the manner that the weight of the engine is distributed upon the driving-wheels and pilot-truck.

5 Having now fully described my invention, I claim—

In a locomotive, the combination of a pilot-truck under the smoke-box, a pair of driving-wheels in front of the longitudinal center of 10 the boiler, between said center and the pilot-truck, and one pair in the rear of the fire-box, with a cylinder equidistant from said driving-wheels, and having a piston therein pro-

vided at each end with a piston-rod, a cross-head, a connecting-rod, and the crank-pin 15 projecting from the driving-wheels, whereby the weight of the locomotive is distributed upon the pilot-truck and the driving-wheels, and the latter are revolved together, substantially as shown and described.

In testimony whereof I affix my signature in presence of two witnesses.

DANIEL R. MURPHY.
